JIMMIE T. IKEDA, OF MINNEAPOLIS, MINNESOTA.

COMBINATION-LOCK.

1,263,062.

Specification of Letters Patent. Patented Apr. 16, 1918.

Application filed April 20, 1917. Serial No. 163,480.

To all whom it may concern:

Be it known that I, JIMMIE T. IKEDA, a subject of the Emperor of Japan, residing at Minneapolis, in the county of Hennepin and 5 State of Minnesota, have invented certain new and useful Improvements in Combination-Locks, of which the following is a specification.

This invention relates generally to locks, 10 and particularly to permutation locks.

The invention aims primarily to provide a lock of the sliding bolt type, wherein improved combination means is employed for locking or releasing the bolt for sliding 15 movement. A further object of the invention is to provide a lock of this character which has its bolt holding parts so arranged as to minimize the opportunity for the unauthorized manipulation of the same, and 20 yet which may be easily actuated by one knowing the proper combination to release the lock bolt.

Still further objects reside in providing a lock of the type set forth which is of simple 25 and inexpensive construction, which is composed of but few readily assembled parts, all of which are so assembled as to minimize the opportunity for wear, breakage, or derangement, which is easy of operation, and which 30 will prove thoroughly efficient in the attainment of the ends for which it is designed.

With these objects in view, together with others which will appear as the description 35 proceeds, the invention resides in the novel formation, combination, and arrangement of parts, all as will be described more fully hereinafter, illustrated in the drawings, and particularly pointed out in the claims.

In the drawings:—

40 Figure 1 is a front elevation of a lock embodying the invention;

Fig. 2 is a longitudinal sectional view taken on line 2—2 of Fig. 1;

Fig. 3 is a similar view taken on line 3—3 45 of Fig. 2; and

Fig. 4 is a detail elevation of the bolt moving disk removed from the lock.

In carrying out the invention, I employ a casing 5 of conventional form, and which is 50 adapted to be secured within a door in any approved manner. This casing is closed at one end by a cover plate 6.

Slidably arranged within the casing is a locking member in the form of a bolt 7, 55 which is adapted when moved to its limit in one direction to be projected at one extrem-

ity beyond the casing, and when moved to its limit in the opposite direction to be wholly confined within the casing. This bolt is provided upon its inner surface with 60 a plurality of shoulders 8, the latter being formed by providing the bolt with transversely extending grooves or channels. The shoulders in the present instance are arranged in separate and distinct sets, there 65 being four of such shoulders in each set.

Extending through the casing at right angles to the lock bolt 7 is a rotatable stem 9, the said stem extending at one end beyond the front face of the casing. This stem carries at its inner end a ring or annulus 10, which is adapted to ride within one of the grooves defining the shoulders 8. In the present instance, this ring comprises a flange turned inwardly from the periphery of a 75 disk indicated at 11, the said disk being attached at its central portion to the stem 9. This flange or ring is notched or cut away as at 12 for a portion of its extent, and the cut out portion is substantially equal in 80 length to the width of the bolt 7. It is obvious from this construction that when the stem 9 is rotated so that the notch 12 is alined with the bolt, the latter will be free to slide, however, when the disk is so positioned that the ring or flange 10 is engaged in the notch or groove in the locking bolt, the latter will be held against sliding movement.

Mounted for rotation upon the stem 9 is 90 a plurality of nested independently movable sleeves 13, 14, 15, and 16; the first three of which are provided adjacent their inner ends with disks 17, from the outer edges of which extend the rings or flanges 18. It will be 95 observed that these disks move concentrically with the pin or stem 9, but vary in diameter. The rings or flanges 18 are also provided with cut away or notched portions 19, and are adapted upon rotation of their 100 respective sleeves to travel within their respective channels or grooves in the locking bolt.

The outer extremities of the nested sleeves project beyond the casing, and each is turned outwardly or flared as at 21. Each of these flared portions provides an annulus 22, and the various annuli are adapted to interfit in the manner shown in Figs. 1 and 2. Handles or grips 23 are provided upon each annulus, 110 so as to enable the same to be easily rotated.

The outer extremity of the sleeve 16 is

provided with a disk, from the edges of which project a flange 25, the latter in its outer face having an annular groove 26 to receive the edges of the innermost of the 5 annuli 22. This flange 25 is also equipped with knobs 27, to facilitate manipulation of the same.

The locking bolt 7 is provided at its inner end with an elongated slot 30, through which 10 the nested sleeves project. The lock bolt is also provided with a longitudinally disposed rack 31, which is adapted to be engaged by the teeth of a rack pinion 32 carried by the outermost of the nested sleeves 16. It is 15 therefore obvious that when unrestricted, the lock bolt may be slid inwardly or outwardly of the casing by rotating the sleeve 16.

It will be observed that each annulus is provided with a series of numbers, and the 20 notches 19 in their respective rings or flanges are adapted to be positioned in register with the shoulders 8 of the lock bolt when the said numbers are in certain positions. When all of the rings have been so 25 moved that their cut out portions are aligned with the locking bolt, the latter is free to slide, and sliding of the bolt is governed by the rotary movement of the sleeve 16 delivered through its flange 25. When, however, any of the flange portions carried by 30 the various disks are engaged either partly or wholly behind any of the shoulders 8, sliding movement of the bolt 7 will be prevented. It is thus seen that accurate adjustment of each annulus 22 must be made 35 before the locking bolt will be released for sliding movement. The grooves forming the shoulders 8 are arranged in separate sets, one of the sets of shoulders being adapted 40 to maintain the bolt in extended or locked position, while the other set of shoulders is to be engaged by the various rings or flanges to hold the bolt in retracted position. It is apparent, also, from this construction, that 45 proper manipulation of the stem 9 is necessary before the bolt will be released to the action of the sleeve 16.

While the present disclosure is that of what is believed to be the preferred embodiment of the invention, it is to be understood that the invention is not limited thereto, but that various changes may be made in the construction, arrangement, and proportion of parts, without departing from

the spirit of the invention, as defined in 55 the appended claims.

What is claimed is:—

1. In a combination lock, a pair of nested independently rotatable sleeves, a disk on one of said sleeves, a notched flange on said disk, a lock bolt having a groove for the accommodation of said flange, the said groove and notch being of equal length, the said lock bolt having a slot through which said sleeves extend, and means governed by the rotary movement of the other of said sleeves for sliding said bolt. 60

2. In a combination lock, a pair of nested independently rotatable sleeves, a notched ring carried by one of said sleeves, a lock bolt having a groove for the reception of said ring, the said bolt having an opening to receive said sleeve, a pinion on the other of said sleeves, and a rack on said bolt in mesh with said pinion. 70

3. In a combination lock, a plurality of nested independently rotatable sleeves in said casing, the outer ends of said sleeves being extended beyond said casing, a notched ring secured to the inner end of each sleeve, 80 a lock bolt having a plurality of grooves to receive said rings, a rack on said bolt, a pinion on one of said sleeves in mesh with said rack, and grip members on the outer ends of said sleeves. 85

4. In a combination lock, a casing, a stem extending through said casing, a plurality of sleeves nested upon said stem and extending at one end beyond said casing, a notched flange carried by each sleeve at the 90 inner end thereof, a lock bolt having a longitudinal slot, the said stem and nested sleeves extending through said slot and supporting one end of said bolt, a rack bar on said bolt, a gear secured to the outermost 95 of said sleeves and in mesh with said rack bar, the said bolt being provided with a plurality of recesses adapted to receive said flanges, and an annulus on the outer end of each of said sleeves whereby the latter may 100 be rotated.

In testimony whereof I affix my signature in presence of two witnesses.

JIMMIE T. IKEDA.
